BOTTLE CLEANING DEVICE

Henry Keller, Astoria, N. Y., assignor to The Best Foods, Inc., New York, N. Y., a corporation of Delaware

Application February 24, 1933, Serial No. 658,308

12 Claims. (Cl. 15—14)

This invention relates to a bottle cleaning device and more particularly to an improved means for applying a jet of air and a vacuum to the inside of the bottle for the purpose of removing 5 dust particles, etc. from within the bottle.

Before using new bottles as containers for food products, it is necessary to subject them to a cleaning process in order to remove any particles of dust, glass, etc. that may be within the bottle. 10 It has been the practice to subject these bottles to washing and drying in order to effect this removal.

It is an object of the present invention to provide an improved device whereby the dust, glass 15 and other particles may be removed by means of a jet of air and the application of suction. Another object is to provide an improved means for controlling the jet of air supplied to the bottles. A further object is to provide an improved arrangement whereby the apparatus may be made 20 available for different numbers and sizes of bottles. Other objects will become apparent.

In describing the invention, reference will be made to the drawings in which Figure 1 represents a perspective view of an apparatus embodying the invention and having six outlets. Figure 2 is a vertical sectional view through the longitudinal center line of a device like that shown in Figure 1 but having only four outlets, 30 the air filter being shown partially in elevation.

Figure 3 is a fractional end elevation of the device. Figure 4 is a transverse section through the center line of the device and Figure 5 is a top plan view of one half of it.

35 In the drawings, the numeral 11 illustrates one of a group of bottles to be cleaned in a single operation of the device. This, and the other bottles to be cleaned during that operation (not shown), are carried upon a section 12 of a conveyor adapted to be moved intermittently longitudinally through the machine by the chains 13, 14 and provided with means for elevating each section when it reaches the position of the section 12a, i. e., when it is immediately beneath 45 the row of air cleaners. This type of conveyor with means for successively elevating the several sections, is old and generally used in apparatus for simultaneously filling groups of bottles.

The cleaning device is made up of a receiving 50 manifold 14 provided with a number of truncated conical or bell-shaped openings 15, each of which openings is adapted to receive the mouth of one of the bottles when the section 12a is in its fully elevated position. The size of each of these openings is so proportioned that when the section 12a

is in its fully raised position there is a small space between the mouth of the bottle and the sides of the opening. This receiving manifold communicates through a fan shaped suction manifold 16 with the intake side of a blower 17 operated by a motor 17a, which blower may be, for example, of the type used in a vacuum sweeper. The air from this blower is conducted through the pipe 18 to a suitable receptacle, for instance, such as a bag similar to those used with vacuum cleaners (not shown).

5 The air jet to be applied to each bottle is introduced through a nozzle 19 adapted to extend to a point near the bottom of the bottle when the section 12a is in its fully raised position. Each of these nozzles is connected to a pressure manifold 20 which in turn communicates with an air filter 21 and, through the pipe 22, with a source of supply of compressed air or other suitable gaseous medium (not shown).

15 The air filter, which may be filled with excelsior packing or other suitable cleansing medium shown at 23 as resting upon a screen 24, is provided with a cross fitting 25, having a baffle 26 so positioned that the air entering through the pipe 22 will pass up through the filtering material and thereafter be discharged through the connection 27 to the manifold 20.

25 The admission of air to the several nozzles 19, 19 is controlled by several ball valves within the manifold 20. In each of these valves the ball 28 is normally positioned in a countersunk inlet to the nozzle, thus closing the opening and preventing discharge of the air. Each of the balls 28 is loosely positioned within a hole 29 in a continuous bar 30. This bar is provided with a rounded bottom surface 31 (see Figure 4) curved to fit the shape of the lower portion of the manifold 20 and adapted to slide around the inner surface thereof.

30 The bar 30 is actuated by a shaft 32 passing through the center of the manifold 20 and provided with holes 33 adapted to loosely receive pins 34 fixed to the bar 30.

35 The shaft 32 may be given an oscillating movement by a lever 35 (Figure 1) fixed to the end of the shaft. This lever 35 is actuated by a cam 36, fixed to a shaft 37, through a lever 38 pivoted in a fixed rod 39 and pivotally connected at one end to a connecting rod 40, which latter is pivotally connected to the end of the lever 35. A roller 41 may be provided at the end of the rod 38 for contacting with the surface of the cam 36 and a compression spring 42 positioned between a stop 43 in the connecting rod 40 and a bracket 44 may

be provided to quickly return the lever 35 to its normal position after it has been depressed by the action of the cam 36.

In operating the improved device, a group of 5 bottles is placed upon a section 12 of the conveyor and as it advances to the position 12a the section of the conveyor and the bottles are raised so that the mouths of the bottles fit loosely within the bell-shaped openings in the manifold and the 10 nozzles 19 extend to near the bottom of the respective bottles. The suction from the blower 17 continuously draws air through the manifold openings 15 around the mouths of the bottles and reduces the pressure at the mouths of the bottles. 15 The shaft 37 is rotated, by suitable means (not shown), in conjunction with the movement of the conveyor so that when the bottles are in their raised position the lever 35 is depressed twice by the action of the cam surface upon the lever 20 38. As the lever 35 is depressed, the rod 32 is rotated in its bearings at the ends of the manifold 25 28 and the pins 34 actuated thereby slide the bar 38 around the inner surface of the manifold to roll the balls 28 out of their seats in the inlets 25 to the nozzles 19 against the pressure of the air tending to hold them in place. When the enlarged portion of the cam has passed the roller 41, the spring 42 returns the lever 35 to its normal position and the rod 32 together with the balls 30 28 are returned to their normal positions and the several valves are closed. The suction is applied continuously and any dust, glass particles, etc. stirred up by the blasts through the nozzles 19, 19 will be drawn out through the manifold 16 35 and discharged through the pipe 18.

Shortly after the second blast of air, the section 12a of the conveyor is lowered to its normal position and the bottles are advanced to the filling machine.

40 As illustrated in Figure 2, the manifold 28 may be provided with additional openings 45 which may be threaded and filled by plugs 46 when the nozzles 19 and the manifold 16 are in use. When it is desired to apply the cleaning device to two 45 bottles of larger size, the nozzles 19 may be removed and plugs similar to the plugs 46 may be inserted in the holes left thereby. The manifold 16 may be removed by unfastening the bolts 50 in the flange connection between the receiving manifold 14 and the suction manifold 16. The receiving manifold 14 may be then replaced by one having only two bell-shaped openings, similar to the openings 15 but centered with the holes 45. The plugs 46 may be removed and two of the 55 nozzles 19 may be inserted in the holes 45. It is apparent that the holes in the manifold 28 may be positioned, and the inlet manifold 14 may be shaped, to take different numbers of bottles of different shapes, and by replacing the manifold 60 with one with suitably positioned openings, many different combinations of sizes and numbers of bottles may be accommodated.

Obviously, many variations may be made in the device, for example, the lever 35 may be so actuated as to open the valves in the pressure manifold more or less often or for a greater or shorter period. If desired, the suction may also be applied intermittently, by providing suitable valves in a manifold connected to a negative 65 pressure tank.

70 It is apparent that other modifications of the invention may be used and it is not intended to limit it to the particular embodiments illustrated and described. The terms used in describing the invention have been used in their descriptive

sense and not as terms of limitation and it is intended that all equivalents thereof be included within the scope of the appended claims.

What I claim is:

1. A device of the type described comprising a suction inlet adapted to receive the mouth of a container and connected to a suction device, a pressure chamber connected with a source of gas under pressure and having a nozzle extending through the opening in the suction inlet, and adapted to extend into the container, ball valve means for normally closing said nozzle, said means being held in a position to close said nozzle largely by the pressure in said chamber, and means for periodically actuating said valve means to suddenly open and close said nozzle to emit a sharp blast from the nozzle. 5

2. A device as defined in claim 1 in which the suction inlet is so shaped as to leave a space around the mouth of the container. 10

3. A device as defined in claim 1, in which the ball fits loosely within an opening in a bar positioned within said chamber, said bar being actuated by a shaft passing through said chamber. 15

4. A device as defined in claim 1 including a plurality of suction inlets, a plurality of nozzles from the pressure chamber, and a ball valve for each nozzle with means for simultaneously actuating said ball valves. 20

5. A device as defined in claim 1 in which said valve actuating means comprises a bar having holes adapted to loosely receive said balls and having pins extending through holes in a shaft positioned longitudinally in said pressure chamber, said bar being adapted upon rotation of said shaft to rotate in said pressure chamber and roll said balls into and out of their seats in the inlets to the nozzles. 25

6. A device of the type described comprising a manifold, a plurality of openings in said manifold, a ball positioned in and adapted to close each such opening, a bar within said manifold having a plurality of holes each adapted to loosely receive one of said balls, means for preventing the balls from falling out of said holes, and means for actuating said bar to simultaneously roll said balls into and out of their normal positions to open and close said openings. 40

7. A valve comprising a ball adapted to normally close a cylindrical opening, a member having a hole within which said ball fits loosely, means for preventing the ball from falling out of said hole, and means for actuating said member to roll said ball out of and into its normal position in the cylindrical opening to open and close said opening, said ball moving axially through the hole in said member as the member moves. 45

8. A device of the type described comprising a chamber, a cylindrical opening in the bottom of said chamber, a ball adapted to normally close said cylindrical opening, a member having a hole within which said ball fits loosely, and means for actuating said member to roll said ball out of and into its normal position in said cylindrical opening, said ball moving upwardly in said hole as the member moves it out of its normal position. 50

9. A device of the type described comprising a pressure manifold having a cylindrical inner surface, a plurality of openings in said manifold, a plurality of balls adapted to fit in and close 55 said openings, a member having a rounded surface adapted to bear upon the inner surface of said manifold, said member having a plurality of openings adapted to loosely receive said balls, means for preventing the balls from falling out 60

of the openings in said member, and means for actuating said member to roll said balls into and out of their normal positions to open and close said openings.

- 5 10. A device of the type described comprising a pressure manifold having a cylindrical inner surface, a plurality of openings in the lower portion of said manifold, a plurality of balls adapted to fit within and close said openings, a member 10 having a curved surface adapted to bear upon the inner surface of said manifold and having a plurality of holes adapted to loosely receive said balls, a rotatable member in said manifold and means connecting said members in such a manner that 15 the rotation of said rotatable member will cause said other member to roll the balls into and out of their normal positions to open and close said openings.

11. A device of the type described comprising a suction inlet adapted to receive the mouth of a container and connected to a suction device, a pressure chamber connected with a source of gas under pressure and having a nozzle extending through the opening in the suction inlet, and adapted to extend into the container, means for normally closing said nozzle, said means being held in closed position largely by the pressure in said chamber, and means for periodically moving said closing means to suddenly open and close said nozzle to emit a sharp blast from the nozzle. 10

12. A device in accordance with claim 11 including means to operate the moving means to open and close said nozzle a plurality of times for each container. 15
